UNITED STATES PATENT OFFICE

ROYAL T. JUMPER, OF BERKELEY, CALIFORNIA, ASSIGNOR TO CALIFORNIA SPRAY-CHEMICAL CORPORATION, OF BERKELEY, CALIFORNIA, A CORPORATION OF DELAWARE

DESIGN FOR A DISPLAY SHELF

Application filed October 23, 1931. Serial No. 41,497. Term of patent 7 years.

To all whom it may concern:

Be it known that I, ROYAL T. JUMPER, a citizen of the United States, and a resident of Berkeley, county of Alameda, State of California, have invented a new, original, and ornamental Design for a Display Shelf, of which the following is a specification, reference being had to the accompanying drawings, forming part thereof.

Referring to the drawings:

Fig. 1 is a perspective of a display shelf in accordance with my invention.

Fig. 2 is another perspective of the display shelf which is illustrated in Fig. 1 but viewed from a different position.

I claim:

The ornamental design for a display shelf as shown.

ROYAL T. JUMPER,
